UNITED STATES PATENT OFFICE.

MARTIN J. BUTZEL, OF BOULDER, COLORADO.

APPARATUS FOR CONCENTRATING AND SEPARATING ORES.

SPECIFICATION forming part of Letters Patent No. 252,731, dated January 24, 1882.

Application filed October 25, 1881. (No model.)

To all whom it may concern:

Be it known that I, MARTIN J. BUTZEL, a citizen of the United States, residing at Boulder, in the county of Boulder and State of Colorado, have invented certain new and useful Improvements in Apparatus for Concentrating and Separating Ores, of which the following is a specification, reference being had therein to the accompanying drawings.

10 My invention consists of a novel apparatus for concentrating gold, silver, and other ores, which will be fully understood by the following description and claim.

In the accompanying drawings, Figure 1 is a side view of my concentrator. Fig. 2 is a detached section of the hollow cone of the concentrator and parts connected therewith. Figs. 3 and 4 are detached views of the hopper or box. Fig. 5 is a detached view of the concentrator and water-tank for receiving heavy concentrates. Fig. 6 represents an end view of the feeding-trough. Fig. 7 is a top view of the skimmer attachment on the top of the concentrator. Fig. 8 is a detached view of a part 25 of one of the inclined boxes for receiving heavy concentrates.

In the drawings, A represents a tank or box for receiving heavy concentrates.

B is the concentrator.

30 C is the feeding-trough.

D is a gutter for conveying off refuse through the pipe E.

F F are boxes or receivers for concentrated material.

35 G is a scaffolding for supporting platform H, through which pass elevating-screws x x. I is a water-tank.

J is a rubber or flexible pipe for conveying water to the concentrator.

40 K is a receiving-pipe for receiving water and the material to be concentrated.

L L are pipes for conveying the material to be concentrated from feed-box C to receiving-pipe K.

45 M is a pipe conveying water to the small pipes N N, which pass through the concentrator and run under the boxes on the inside thereof. These pipes are perforated and throw fine jets of water toward the inside of the concentrator to prevent any light particles from

being thrown into the boxes before they reach their proper level.

O is a regulating stop-cock to increase or diminish the quantity of water conveyed to pipe K.

55 P P are stop-cocks for regulating the supply of material to be concentrated.

S S are faucets draining tank A.

R R are stop-cocks on faucets S S.

T is a man-hole through which heavy material is removed from tank A.

60 U U are traps or covers of the ends of boxes F F, through which concentrated material is removed.

x x are screws for elevating and lowering tank I.

Y is a lever for working screws x x.

4 is a stop-cock for regulating the supply of water through pipe M. a a are screws to secure covers to boxes and the man-hole to pipe M.

70 Z is a skimmer attachment to be fastened on the top of the concentrator when treating tellurium ores or other substance where valuable particles are liable to rise to the surface.

a' a' is the inner rim of the iron skimmer. 75 b b is the outer rim of skimmer. c c are thumb-screws for raising or lowering the skimmer so

as to take only the surface part of the overflow, while the rest passes under the skimmer and over the rim of the concentrator.

80 g g is a fine wire screen to save valuable particles on the surface of the overflow.

h h are cross bars or rods for connecting outer rim, b b, with inner rim, a' a', and supporting the screen g g.

85 Fig. 8 represents a section of one of the boxes or concentrators F, showing the fastening of the trap or cover U.

d is an iron bar passing across the end of the box on the inside with a screw-hole in the center of said bar.

90 5 is a screw passing through the trap or corner of the box into the screw-hole in the center of bar d d to fasten said trap or cover.

95 The pulverized ore is placed in box C, and sufficient water added thereto to make a thin flowing mortar or pulp, the concentrator B having been previously filled with water from the reservoir I by means of pipe J. The pulp flows from box C down the pipes L, and rises 100

in the cone of the concentrator round the central space, z , Fig. 7, and covering the screen $g\ g$. The overflow passes off by trough D and pipe E, Fig. 1. The heavy concentrates settle 5 down according to their specific gravity in the inclined outside boxes or receivers, F, and are afterward removed by opening the traps U, Fig. 8. The heavy concentrates which settle in tank A, Fig. 1, are removed through man-
10 hole T.

By this apparatus I not only concentrate but also separate different minerals according to their specific gravity, the heavier being found in the lower boxes or receivers F, while 15 the lighter materials pass into the upper receivers F.

Having thus described my invention, I claim—

The concentrator B, provided with the series of receivers F, in combination with the 20 water-supply pipe O, ore-conveying pipes L, the water-pipe J, and tank I, the several parts being arranged with relation to each other, substantially in the manner as and for the purpose herein shown and described. 25

In testimony whereof I affix my signature in presence of two witnesses.

MARTIN J. BUTZEL.
